UNITED STATES PATENT OFFICE

2,667,459

MECHANICAL FOG GENERATOR

William J. Besler, Piedmont, Calif.

Application November 13, 1947, Serial No. 785,635

4 Claims. (Cl. 252—359)

1

There has been an increasing demand for smaller, portable units for making artificial fog and the present invention represents further improvements upon my two co-pending applications, the first of which is serially numbered 532,292, filed February 21, 1944, which issued as Patent Number 2,432,372 on December 9, 1947, this application being a continuation in part thereof, and the second of which was filed November 12, 1947, and is serially numbered 785,351, now Patent No. 2,630,412.

Among the objects of the present invention is the creation of a device which, using steam as a vehicle, will produce a thick, impenetrable, obscuring fog for military purposes in covering military objects and movements.

Similarly it is an object of the present invention to produce such a fog but which at the same time may be breathed for extended periods by humans and animals without injurious effects.

Another object of the present invention is to produce an artificial fog which is non-combustible even though produced from a combustible source material. A still further object of the present invention is to provide a quick acting, compact machine for generating a maximum volume of fog in a minimum period of time and with a minimum of supervision.

It is also an object of the invention to provide a device which has peace time uses and which can be operated as an insecticide disseminator or as an artificial aerosol for the protection and treatment of crops, vegetation and the like and for the extermination of harmful insects.

A further object is the coordination of the fuel supply of the fog oil supply and the water supply to the motive means, and the utilization of the products of combustion from the motive means, all in a most efficient manner.

Further objects are to provide a construction of maximum simplicity, economy and ease of assembly and disassembly and such further objects, advantages and capabilities as will fully appear and as are inherently possessed by the device and invention described herein.

The invention further resides in the combination, construction and arrangement of parts illustrated in the accompanying drawings, and while there is shown therein a preferred embodiment it is to be understood that the same is illustrative of the invention and that the invention is capable of modification and other uses and comprehends other details of construction without departing from the spirit thereof or the scope of the appended claims.

2

In the three sheets of drawings:

Figure 1 is a side elevation from the blower side of a mechanical fog generator constructed in accordance with this invention, a portion of the generator being broken away and shown in vertical section.

Figure 2 is a plan view from above of the same.

Figure 3 is a diagrammatic perspective of the same showing the liquid systems, the motor assembly being omitted.

Figure 4 is an end elevation of the assembled device from the system's end.

Figure 5 is an enlarged detail in vertical section of the thermostatic fuel control valve.

Figure 6 is an enlarged detail in vertical section of the feed water regulator.

Figure 7 is an enlarged vertical section of the manual fog oil valve.

20 The detailed structure of the device of the present invention shown in the drawings is best understood by reference to Figures 1 and 3. Essentially it is divided into three component organizations, the first of which is the base 10, 25 the second of which is the steam generator 11, and the third of which is the group of systems arranged on the base at the opposite end from the steam generator 11.

The base 10 is preferably a tank which is divided into two non-communicating compartments by the wall 12. When used as a fog machine as here described, the water tank is compartment 14 and the fuel tank is compartment 15. Each tank has its separate filling spout and cap, the one for water being designated 16 and the one for the fuel, 17. While the drawings indicate that the base 10 may be one tank divided into individual compartments, it is obvious that it also may be built up by welding or otherwise securing two or more tanks together into an integral unit.

Since portability is one of the important features of the present device, the base 10 is provided with brackets 18 at each of the four corners thereof near the top through which handles 20 45 and 21 are slideably mounted. For purposes of structural strength the base may be provided with reinforcing ribs 22 at spaced intervals.

The generator 11 has a cylindrical air casing 23, the lower edge of which is welded or secured 50 in any other suitable manner to the top 24 of the base 10. Above the air casing 23 is a flue pan 25. The meeting edges of the flue pan and the air casing are flanged outwardly and held together by girth band 26, the ends of which are 55 drawn together by the turn buckle or clamp bolt

27. The flue pan 25 is provided with an offset outlet 28 for the escape of the waste products of combustion from the boiler. The interior wall of the air casing 23 is insulated as at 30 and also at the bottom as at 31. The cylindrical combustion chamber 32 has a vertical wall 33 spaced from the insulation 30 to provide air space 34. The combustion chamber has a bottom 35 secured to the vertical wall thereof having a central opening 36. The opening 36 leads to a primary combustion chamber 37 which is cylindrical in shape having a vertical wall 38 and a bottom 40 which depend from and are secured to the bottom 35 of the combustion chamber 32. The burner assembly 41 passes through the insulated air casing wall and into the primary combustion chamber 37, the same being mounted upon the burner flange 42 for ease of assembly and disassembly. The burner assembly includes a spark plug 43 which provides the ignition for a vaporizing fuel. Combustion air is supplied by a blower (not shown) contained within the blower housing 44 having a screened air intake 45. The blower delivers combustion air tangentially through a duct leading from the blower housing 44 through the insulated air casing 30 into the air space 34. From there the air passes through a series of louvers 46 in the vertical wall 38 of the primary combustion chamber 37. The products of combustion pass upwardly through the opening 36 through the chamber 32 where combustion is completed. The hot combustion gases pass upwardly through the spaced coils 47 to 52 and are dissipated to atmosphere through outlet 28 in flue pan 25. It is to be noted that the outlet 28 is offset and that the flue gases are deflected by the baffle 53. This is done so that the generator has better efficiency characteristics and also to prevent, to a very large measure, the glow resulting from the heating of the metal.

30. The vapor generating surface of the boiler consists of a series of flat spiraled or pancake coils 47 to 52 interconnected to form a continuous passage from inlet to outlet. The inlet passage 54 leads directly to the uppermost coil 47 and the flow is progressively downward or in counterflow relationship with respect to the combustion gases. This series of coils is supported upon an inward annular indentation 55 in the wall 33, the curvature of the spiral being such at this point that it does not show the lowermost coil resting thereon in Figure 1.

35. The lowermost coil 52 discharges at 56 into a horizontal run of tubing 57 which contains the thermostatic tube 58. The flow then goes upwardly substantially on the axis of the boiler through discharge tube 60, out through the flue pan 25 to the manifold 61 which is provided with a series of jets 62 through which the generated vapor and its entrained material is released and expanded into a heavy fog into the surrounding atmosphere, all as is more fully explained hereinafter.

40. A gasoline engine 63 is used as the means for driving all of the systems of the device. The blower fan within housing 44 is driven directly from the shaft of the engine. The shaft also has a sprocket thereon for driving the sprocket chain 64 encircling the sprocket 65 for driving the pump 66. When the device is used as here shown for the making and dissemination of fog or a fine aerosol, five systems are involved in its operation.

The gasoline system

45. This system supplies fuel to the engine 63 and

to the burner assembly 41. When the engine 63 is started the gasoline pump 67 which is an integral part of the engine, produces suction drawing gasoline from the tank 15 through line 68 in which is interposed a strainer 70. Flow of the gasoline or other vaporizing fuel after passing through the pump 67 is divided in its flow in two directions. One portion 71 goes to the engine carburetor (not shown) and the other goes via line 72 to the thermostatic fuel valve 73. When the unit is cold the thermostatic fuel valve is open permitting free passage of the fuel to line 74 leading to the fuel control valve 75 which is closed until the burner 41 is to be started. When the burner fuel valve 75 is open the vaporizing fuel flows through a control orifice 76 which limits the amount of fuel for full fire and passes in line 77 to the burner assembly 41 where it is vaporized and mixed with air and ignited by the spark plug 43 to produce a long torch-like flame within the primary combustion chamber 37. It will be observed at this point that the line 77 passes inside of pipe 78 which conducts the exhaust from the engine 63 to the burner assembly where it not only warms the burner, insuring prompt starting in cold weather, but also warms the fuel on its way to the burner assembly.

The water system

50. When the engine is started a fog oil-water pump produces suction which draws water from tank 14 up through line 80 in which is interposed strainer 81, to the feed water regulator 82 (see Figure 6). The water enters through a restricted orifice 83 and leaves through needle valve 84. The feed water regulator comprises a body member 85 with a flanged cap 86. A flexible diaphragm 87 is held between the body member and the cap to form a pressure and liquid-tight gasket around its periphery. Plates 88 and 89 reinforce the central portion of the diaphragm. The needle valve 84 is fixed in the plates in the center of the diaphragm in registry with the valve seat 90 adjacent the outlet 91 leading to the pump 66. The valve 84 is normally held open by the coil spring 92. The needle valve is provided with an adjusting nut 93. Cap member 86 is vented to the atmosphere through vent 94. A pet cock 95 is provided in the valve housing 85 as a means for draining the same should this be required.

55. As stated above the valve 84 is normally held open by the spring 92. However, when the engine has been started and the suction increased to one pound per square inch the diaphragm is acted upon by the suction to compress the spring, partly closing the valve 84, thus preventing an over supply of water by maintaining a constant suction on the regulator body. In other words the regulator maintains a uniform pressure drop across the orifice 83 thereby maintaining a uniform water delivery. The water so delivered enters the line 96 to the pump 67 through the three-way valve 97.

The fog oil system

60. This system supplies the fog oil to the generator 11. The fog oil is introduced into the system by means of the fog oil-water pump 66. Usually the fog oil or other material to be put through the generator is supplied in separate drums or tanks. The device is supplied with flexible hose 98 for introduction into the source of fog oil supply and the suction of the pump forces it through the fog oil filter 100 and if the three-way valve 97 is in the "on" or fogging position, the fog oil will be delivered to line 96 where it

mixes with water coming from the feed water regulator 82. The mixing usually takes place before passing through the pump 66 but in any event thorough mixing is completed by the pump which delivers the mixture to line 101.

The electric system

The electrical system consists of a magneto driven by the engine 63 which supplies current not only for the spark plug on the engine but also to the spark plug 43 in the burner for ignition. A single switch (not shown) on the engine housing will cut off the spark in both instances.

The combustion air system

As stated before, this system draws air from the outside through the air inlet 45 of the fan casing 44 and delivers it to the air space 34 inside the air casing 23.

The operation of the device is as follows. The handle 102 on the three-way valve 97 is placed in the vertical position. (Horizontal position in Figure 7 is in the direction of the arrow.) The engine 63 is then started and immediately thereon the systems begin to function. The suction of pump 66 delivers water to the feed water regulator 82 in the manner previously described. However, since the valve 66 is in the vertical or "off" position, water will pass directly through this valve via transverse passage 103 and into the pump via line 96. Water is immediately supplied to the coils through line 101 which joins with inlet line 54. The vaporizing fuel is delivered by pump 67 to the engine carburetor and the thermostatic fuel control valve 73. The blower also starts and air is supplied to the generator for combustion purposes as described above. The motor 63 is run for a few moments so that the exhaust gases will warm the supply line 77 and the burner assembly 41 before the fuel is manually turned on at valve 75. The exhaust gases from the engine are led through the line 78 to a point beneath the burner assembly. The heat of the exhaust gases assists in the vaporizing of the fuel. The exhaust gases do not however mix with the gasoline or vapor in the burner assembly. Within a few seconds after the engine is started the burner valve 75 may be opened permitting the vaporizing fuel to pass through the restricted orifice 76 to the burner assembly 41 through line 77.

As soon as the burner fuel valve 75 is opened, fire will come on in the combustion chamber 37 at the full rate for the operation of the device. As soon as the generator has come up to operating temperature, the fire will automatically reduce itself to low fire which will be maintained during the entire operation. The fog oil may now be introduced into the system by moving the handle 102 on valve 97 to the horizontal or "on" position shown in Figures 1, 2, 3, and 4. In Figure 7 the valve is shown in the "on" position. In this position the pump 66 pumps fog oil through the flexible tubes 98 through the filter 100 through the fog oil intake 104 in the valve through the lateral passage 105 to the line 96. Since the valve 97 is of the tapered plug type, the upper proportion of water measured by the feed water regulator is delivered through the valve by by-pass groove 106 where it mixes with the fog oil in the line 96 on the way to the pump.

The mixture of fog oil and water is delivered to the first of the coils, 47, in the generator through lines 101 and 54 and passes successively

through the coils 47, 48, 50, 51 and 52 in substantially a counter-flow path with respect to the products of combustion from the combustion chamber 32. In these coils the water is quickly transferred to superheated steam and vaporizes some of the oil. The flow then passes from coil 52 where it discharges at 56 into the straight length of tube 57 containing the thermostatic tube 58. From thence it passes upwardly through outlet tube 60 to the manifold 61 where it is released to atmosphere through the nozzle 62. The result is an immediate, dense persistent and covering fog which is neither inflammable nor injurious to respiration.

15 Thermostatic control valve 73 is provided to control the supply of fuel to the burner assembly 41, in order to maintain automatically the proper temperature at the outlet for the fog making fluid. This valve has a fuel inlet 110 and a fuel outlet 111 closed by the diaphragm 112 under spring pressure on the valve head 114 above the outlet. The valve head 114 has its stem 115 in contact with a bell crank 116 which is pivoted at 117 and depressed by the spring 118 attached to the surrounding case 120. The arm 121 of bell crank 116 bears against the thermosensitive rod 122 which extends through and is secured in the tube 58. It is apparent by adjusting the length of the stem 115 the closing of the fuel valve can be accomplished for any temperature required. As stated above, this valve is open at the start so that vaporizing fuel is free to pass therethrough. However, as the temperature approaches the setting only enough fuel will pass through the valve 73 to maintain the temperature of the setting. The unit comes up to temperature very quickly and as the tube 58 expands with the heat it will expand more rapidly than the thermostatic element 122 increasing the tension of the spring 118 on the stem 115. In this manner the flow of vaporizing fuel through the valve 73 is reduced and stopped altogether when the temperature has reached the temperature of the setting. When the temperature drops the tension on spring 118 is reduced opening the valve 73 and reestablishing fire in the burner. In this manner automatic control is maintained for the entire operation. When the device is used for fogging purposes the thermostatic control valve is set to close at 900° F. which means that the valve 73 will open and remain open just enough to permit passage of fuel to maintain the temperature at this setting.

55 The fog oil used for fogging purposes and for fine aerosol is a highly refined lubricating oil or any oil which responds to the Chemical Warfare Service code designation SGF.

At a pump speed of approximately 1,000 R. P. M. and a ratio of water to fog oil of 1:8.5 or 1:9 with an operating temperature of 900° F. the device will produce fog having a particle size of from .1 to .3 micron radius in less than one minute from a cold start.

65 The peace time uses of the device normally require a larger particle size in order to give better local control of the travel of the aerosol. It has been discovered that the size of the entrained particle released with the steam vehicle from the nozzle jets 62 is a function of the operating temperature of the device. Thus aerosols having a particle size from 2 to 10 microns radius for example, are obtained by operating the device at temperatures ranging between 450° to 550° F.

As is amply demonstrated by the foregoing the function of the water system in the operation of

the device is to provide the steam vehicle for the dissemination of entrained particles. If the machine is to be used for the dissemination of insecticides, the insecticide emulsion already contains the proper proportion of water. Hence it is not necessary to use the water system which may be either disconnected or removed entirely without altering the function or operation of the device. No matter how it is used, it is the steam produced by the generator which is the vehicle for securing an aerosol or fog. If fog is being made the result will be a dense, persistent, covering, white fog or aerosol. On the other hand if an insecticide emulsion is being put through the device the result will be a thick, cloud-like fog which carries the lethal dosage to every portion of the trees or crops or whatever may be the object of the treatment. It should be noted that in use the manifold 61 may be mounted with a universal joint and aimed in any direction desired.

I claim:

1. A device for producing an artificial aerosol comprising in combination a vapor generator including a fluid circuit therein arranged for counterflow with respect to heat from the burner, and a burner for a vaporizing fuel, auxiliaries including a constant speed engine for simultaneously driving several units comprising a pump for supplying the vaporizing fuel to the engine and the burner, a blower for supplying combustion air to the generator, and a pump for supplying operating fluid to said fluid circuit, a water regulating valve communicating with the suction side of said pump and operable to supply water thereto in response to the negative pressure thereof to maintain delivery of a constant ratio of operating fluid and water, and restricted orifices for releasing the vapor and entrained particles of operating fluid at the outlet end of the fluid circuit on the outside of the generator to produce an artificial aerosol.

2. A device for producing an artificial fog comprising in combination a vapor generator including a fluid circuit therein for vaporizing the operating fluid arranged for counterflow with respect to heat from the burner, and a burner for a vaporizing fuel, auxiliaries including a constant speed engine for simultaneously driving several units comprising a pump for supplying the vaporizing fuel to the engine and the burner, a blower for supplying combustion air to the generator, and a pump for supplying the operating fluid comprising a mixture of water and fog oil in a predetermined ratio to said fluid circuit, a water regulating valve communicating with the suction side of said pump and operable to supply water thereto in response to the negative pressure thereof to maintain delivery of a constant ratio of operating fluid and water, thermostatic means within and adjacent the outlet end of said fluid circuit for controlling the flow of vaporizing fuel to said burner, and nozzles for releasing the vapor and entrained particles of operating fluid at the outlet end of the fluid circuit on the outside of the generator to produce an artificial fog.

3. A portable device for producing an artificial

fog comprising in combination a base having noncommunicating compartments, a boiler including a fluid circuit and a burner using vaporizing fuel mounted toward one end of said base, ignition means for said burner, an internal combustion engine for simultaneously driving a series of units, all mounted toward the opposite end of said base, comprising a pump for supplying a vaporizing fuel from one of said compartments to said engine and said burner, a pump for supplying the operating fluid comprising fog oil and water to said fluid circuit, and a normally open water regulator interposed between a water compartment and said pump and responsive to the negative pressure thereof to deliver water in ratio to the volume of fog oil delivered thereby maintaining a constant mixture of operating fluid, manual means for setting the maximum operating outlet temperature for said fluid circuit, and thermostatic means for automatically shutting off the supply of vaporizing fuel to the burner when the said set temperature is reached, and maintaining a flow of said fuel when the temperature is below said setting.

4. A portable device for producing an artificial aerosol comprising in combination a base having noncommunicating compartments for water and fuel, a boiler including a fluid circuit and a burner using vaporizing fuel mounted toward one end of said base, ignition means for said burner, an internal combustion engine for simultaneously driving a series of units, all mounted toward the opposite end of said base, comprising a pump for supplying a vaporizing fuel from said fuel compartment to said engine and said burner, a blower for supplying combustion air to the burner, a pump for supplying the vaporizing mixture comprising fog oil and water to said fluid circuit, and a water regulator valve interposed between the water compartment and the suction side of said pump, having an inlet orifice and a normally open outlet responsive to the negative pressure of said pump to deliver water in ratio to the volume of fog oil delivered thereby maintaining a constant mixture of vaporizing mixture, nozzle means for releasing the vapor and its entrained particles at the outlet end of said fluid circuit outside said generator to produce an artificial aerosol, manual means for setting the maximum operating outlet temperature for said fluid circuit, and thermostatic means for automatically shutting off the supply of vaporizing fuel to the burner when the said set temperature is reached, and maintaining a flow of said fuel when the temperature is below said setting.
